Patented July 20, 1920.

40 37 Inventor:
Fig. 7. By John Repetto.
J. Stuart Freeman,

UNITED STATES PATENT OFFICE.

JOHN REPETTO, OF PHILADELPHIA, PENNSYLVANIA.

FLUID-COCK.

1,346,977.

Specification of Letters Patent.

Patented July 20, 1920.

Application filed August 28, 1918. Serial No. 251,732.

To all whom it may concern:

Be it known that I, JOHN REPETTO, a citizen of the United States, residing at Philadelphia, in the county of Philadelphia and 5 State of Pennsylvania, have invented certain new and useful Improvements in Fluid-Cocks, of which the following is a specification.

This invention relates to valves, and particularly to that class which is employed to regulate the flow of illuminating and heating gas.

The object of the invention is to provide an improved and extremely simple means 15 whereby the accidental turning-on of the valve is eliminated by providing a gravity-actuated latch mechanism attached to the valve-operating member.

Another object of the invention is to provide, in addition to the foregoing, and particularly in conjunction with those valves employed to regulate the flow of gas for heating and cooking purposes, means 20 for indicating the extent to which the valve is open without necessitating the usual opening of an oven door in a gas-range, or the usual stooping over in order to determine this fact in viewing the height of the flame beneath a vessel over a flame.

A still further object of the invention comprises pivotally mounting upon the usual handle of a fluid valve, a latch provided with a weight, operative to normally maintain the former in the lowermost position permitted by a recessed guide, and to provide said latch with a manually actuated extension adjacent to one side of the usual valve handle.

These and other objects and details of the 25 construction of the preferred embodiment of the invention are fully brought out, when read in conjunction with the accompanying drawings, in which Figure 1 is a side elevation of one embodiment of the invention as applied to a gas fixture used for illuminating purposes; Fig. 2 is a section on the line 2—2 of Fig. 1 in the direction of the arrow; Fig. 3 is a fragmentary top plan view of the valve portion of the device shown in Fig. 1; Fig. 4 is a development of the notched latch 30 guide; Fig. 5 is an elevational view of the device as applied to a valve of a range, or the like, used for heating and cooking pur-

poses; Fig. 6 is a top plan view of the same; and Fig. 7 is a development of the notched 55 guide used in connection with this form of the device.

Referring to Figs. 1 to 4, inclusive, of the drawings, a gas fixture is shown as comprising a section of a pipe 10, including a valve housing 11, and extending from the wall 12, while to the outer transversely bored end 13 of which pipe is pivotally secured a similarly bored member 14, through one end of which latter extends a tube 15, carrying upon its outer free end any common or well-known form of gas-jet 16.

Within the housing 11 is revolvably mounted the usual valve held in position by a screw 17 and manually operated by means 70 of a thumb-lever 18. Extending through this lever, and pivotally connected thereto at 19, is a latch member 20, preferably provided at one end with a suitable weight 21 and at its opposite end with a depending 75 extension 22, adapted to be actuated by the fingers as they grip the lever 18 for the purpose of opening the valve and regulating the flow of gas therethrough.

Extending downwardly from the pipe 10, 80 and concentrically with the housing 11, is a substantially semi-circular member 23, provided with a slot 24 extending horizontally through an arc of 180 degrees, and said slot at its opposite ends being provided 85 with a downwardly extending offset 25, into which the member 20 operates by gravity to force the latch, in order to maintain the same, together with the valve, with which it moves in exact unison, in either extreme 90 closed position. Thus, it is obvious that with this construction, it would be difficult to accidentally open the gas-regulating valve with a consequent prevention of at least many of the accidental cases of asphyxia- 95

Referring now to Figs. 5 to 7, inclusive, a main gas supply pipe 30 is shown from which leads a nipple 31, connected at its opposite end to the common form of valve 100 casing 32, through which is revolvably mounted a valve 33, provided with a handle 34 and through which extends an aperture 35 for a purpose hereinafter described. The side of the casing 32, opposite the nipple 31, 105 is provided with an extension 36 leading

I claim and desire to protect by Letters Patent of the United States is:—

45

1. A device of the character described comprising, a casing, a valve therein and having a stem, a stationary plate arranged near the casing and provided with a slot, said slot having its outer wall provided with notches, and a lever pivotally connected with the stem and having a portion thereof adapted for movement away from the casing to engage a selected notch in said outer wall.

50

2. A device of the character described comprising, a casing, a valve therein and having a stem, a stationary plate arranged near the casing and provided with a slot, said slot having its outer wall provided with notches, a lever pivotally connected with the stem and having one end portion thereof arranged within the slot and adapted to move away from the casing to engage a selected notch in the said outer wall, and a weight secured to the opposite end portion of the lever.

55

3. A device of the character described comprising, a casing, a valve therein having a stem, a crank secured to the stem and provided near its free end with a transverse opening, a stationary plate arranged near the casing and having a slot, said slot being provided upon its outer wall with a plurality of notches, a lever pivotally connected between its ends with the stem and having one end thereof projecting into the slot, such end being adapted for movement away from the casing into engagement with a selected notch in said outer wall, the opposite end of the lever having a transverse portion extending through the transverse opening in said crank, and a weight secured to the free end of the transverse portion.

In testimony whereof I have affixed my signature.

JOHN REPETTO.

through the side wall 37 of an oven, or the air-mixing chamber thereof, which latter in turn leads into an oven, or into any well-known form of gas-burner.

5 Secured to, and extending upwardly from, the valve casing 32 is a member 38, provided with a slot 39 preferably extending horizontally through an arc of 90 degrees, and provided with two upwardly extending offsets 40, into which one end portion of a lever 41 is adapted to be moved, while the position of the handle 34 corresponds with the extreme open and closed positions of the valve 33. The lever 41 is pivotally mounted at 42 upon the said valve and extends above and longitudinally along the said handle, and thence preferably passes downwardly through the aperture 35 in the latter, and at its lowermost end portion is provided 20 with finger-engaging enlargement 43.

In the operation in this form of the device, gravity acting upon the longer arm of the lever 41 and enlargement 43 tends to maintain the shorter arm of said lever in contact with the upper edge of the slot 39 in the member 38, said edge being provided, in addition to the offsets 40, with spaced saw-teeth offsets 44. Thus the engagement of said lever with one of the offsets 40 insures the maintenance of the valve in either extreme open or closed position until released therefrom by upward pressure of a finger upon the enlargement 43. Also, as the handle 34 is oscillated to and fro, and the shorter arm of the lever 41 passes successively into the offsets 44, it is easy to determine the degree to which the valve is open, or closed, without necessitating the opening of the oven door or stooping over 30 to observe, in the case where an exposed gas-burner is beneath a vessel being heated, the condition of the flame.

Having thus described my invention, what
